(57) **CLAIM**

The ornament design for a body shape for keyboard, as shown and described.

DESCRIPTION

FIG. 1 is a perspective view of a body shape for keyboard showing our new design;

FIG. 2 is a top view thereof;

FIG. 3 is a left side view thereof;

FIG. 4 is a right side view thereof;

FIG. 5 is a front view thereof;

FIG. 6 is a rear view thereof; and,

FIG. 7 is a perspective view of the keyboard of FIGS. 1-6 without the presence of certain disclaimed subject matter;

FIG. 8 is a top view thereof;

FIG. 9 is a left side view thereof;

FIG. 10 is a right side view thereof;

FIG. 11 is a front view thereof; and,

FIG. 12 is a rear view thereof.

The broken line showing of the lower portion of the keyboard and other regions is for illustrative purposes only and forms no part of the claimed design.
